(57) **CLAIM**

The ornamental design for a hose coupling, as shown and described.

DESCRIPTION

FIG. 1 is a top view of a hose coupling in accordance with our design;

FIG. 2 is a top, front perspective view thereof;

FIG. 3 is a top, rear perspective view thereof;

FIG. 4 is a bottom view thereof;

FIG. 5 is a bottom, front perspective view thereof;

FIG. 6 is a bottom, rear perspective view thereof;

FIG. 7 is a rear elevation view thereof;

FIG. 8 is a right side elevation view thereof;

FIG. 9 is a front elevation view thereof; and,

FIG. 10 is a left side elevation view thereof.

The broken lines depict portions of the article that form no part of the claimed design.

1 Claim, 10 Drawing Sheets
